UNITED STATES PATENT OFFICE

OLAN BEVERLY UNDERWOOD, OF EVANSVILLE, INDIANA, ASSIGNOR TO BERNARDIN BOTTLE CAP CO., OF EVANSVILLE, INDIANA, A CORPORATION OF INDIANA

DEVICE FOR SEALING CONTAINERS UNDER VACUUM

Application filed July 24, 1931. Serial No. 552,909.

The invention relates to devices for sealing containers with screw caps under vacuum.

One object of the invention is to provide a simple device for this purpose which can be easily and manually manipulated and is equipped with a handle which may be grasped in one hand of the operator to hold the casing in air-tight relation with the container and with means adapted to be operated by the other hand for screwing the cap onto the container while it is under vacuum. Another object of the invention is to provide a device for this purpose with a valve for the vacuum connection which is within reach of the hand of the operator grasping the handle. Other objects of the invention will appear from the detailed description.

The invention consists in the several novel features hereinafter set forth and more particularly defined by claims at the conclusion hereof.

In the drawing: Fig. 1 is a vertical section of a device embodying the invention. Fig. 2 is a plan.

The invention is exemplified in a device comprising a casing 3 of cast metal, the lower end of which is open and is provided with an inset elastic band or gasket 4 which is adapted to engage the shoulder on a container *a* to form an air-tight closure between the casing and the container when the latter is held on the container. The upper end of the casing has a closed wall 5 to enclose and form a closed chamber 6 around the upper portion of the container which is provided with an external screw *a'* for a screw cap *b* with a depending screw threaded flange *b'*. A handle 7 projects laterally from and is formed integrally with the casing 3. The handle is adapted to be grasped by the operator to hold the casing 3 downwardly against the container *a* during the sealing operation. A vacuum connection for exhausting the air from the container *a* and chamber 6 in the casing comprises a flexible tube 8 which is connected to a vacuum tank (not shown) and to a nipple 9 in the outer end of the handle and a port 10 extending longitudinally through the handle to the

chamber 6. A cylindrical valve 11 is vertically slidable in a socket 12 formed in the handle adjacent the casing 3, to control the vacuum connection and the admission of air to the chamber 6 after a sealing operation has been completed. This valve is provided with a horizontal port 13 which, when the valve is depressed, registers with the port 10 to connect the chamber 6 to the vacuum tank to exhaust the air from the container and chamber 6. A stem 14 extends upwardly from valve 11 and is provided at its upper end with a button 15 which is adapted to be pressed by the thumb or a finger of the hand of the operator which is used to grasp the handle 7. Valve 11 is normally held in its raised position by a spring 16. This spring holds the valve normally closed or in position to interrupt the suction connection until the operator depresses the button 15. A pin 17, secured to the button, slides in a socket 18 in a boss 19 formed on the handle to hold the valve against rotation. This valve also controls the admission of air to the chamber 6 to release the vacuum therein at the end of a sealing operation or when the valve is in its normal position. For this purpose a port 20 leads from the chamber 6 in the casing 3 to an angular port 21 in valve 11. When the valve is depressed port 20 will be closed, and when the valve is retracted to its normal position, port 21 will register with port 20 to admit air to the chamber 6 to release the vacuum.

A head or chuck 23 in the casing 3 has a tapered socket 24, the inner periphery of which is adapted to engage the corner or side of the screw-cap *b* for the purpose of rotating the cap to close the seal while the chamber 6 is under vacuum. This head is secured to the lower end of a stem or shaft 25 which extends through the top wall 5 of the casing and a stuffing box 26. A hand wheel 27 is fixed to the upper end of the stem 25. Stem 25 is slidable and rotatable in its bearing in the casing, so that the head 23 may be pressed downwardly to engage the cap *b* and then turned to rotate the cap.

The operation of the device is as follows: The operator will grasp the handle 7 with

one hand, usually the left, and press the casing 3 downwardly against the shoulder on the container to enclose the upper portion of the container on which a screw cap has 5 been loosely placed and to close the chamber 6. When that has been done, the operator will depress button 15 with a thumb or a finger of the hand grasping handle 7 to shift valve 11 to bring port 13 into registry with 10 port 10, so that the chamber 6 will be in communication with the vacuum tank. The valve will be held in this position until the container has been vacuumized to the desired degree. The operator will then press down- 15 wardly and turn wheel 27 with his other hand to force the head 23 into engagement with the screw-cap *b* and rotate it to seal the container or jar *a*. After the screw-cap has been thus secured, the operator will release 20 button 15 so that spring 16 will close valve 11 and cut off the vacuum tank from the chamber 6. When the valve reaches its normal raised position, its port 21 will register with port 20 to permit air to enter the chamber 25 6 and break the vacuum therein. The casing 3 can then be readily removed from the sealed container.

The invention exemplifies a device for sealing containers with screw-caps under pressure, which is simple in construction and can 30 be easily manipulated by a single operator.

The invention is not to be understood as restricted to the details set forth, since these may be modified within the scope of the appended claims, without departing from the 35 spirit and scope of the invention.

Having thus described the invention, what I claim as new and desire to secure by Letters Patent, is:

40 1. In a device for sealing with a screw cap a container having a reduced externally threaded neck and a shoulder beneath the neck, the combination of a casing designed to form a closed chamber around the upper 45 portion of the container and comprising a top wall adapted to overlie the neck of the container and a continuous side wall depending from the top wall and adapted to surround the neck and rest directly upon the 50 shoulder of the container, a handle connected to and projecting from one side of the casing whereby the casing may be held in place with the continuous side wall resting upon the shoulder of the container, a vacuum 55 connection for the chamber comprising a flexible tube connected to the outer end of the handle and a duct extending longitudinally through the handle, a valve in the handle for controlling the duct, a head disposed within 60 the chamber and having a conical socket in the under part thereof for receiving the cap, and means on the outside of the casing whereby the head may be manually operated to screw the cap on the neck of the container 65 while the casing is under vacuum.

2. In a device for sealing with a screw cap a container having a reduced externally threaded neck and a shoulder beneath the neck, the combination of a casing designed to form a closed chamber around the upper 70 portion of the container comprising a circular top wall adapted to overlie the neck and an annular or cylindrical side wall depending from the marginal part of the top wall and adapted to surround the neck of the container and rest directly upon the shoulder, a handle connected to and projecting outwardly from the side wall of the casing whereby the casing may be held in place with the side wall resting upon the shoulder of 75 the container, a vacuum connection for the chamber comprising a flexible hose connected to the outer end of the handle and a port extending longitudinally through the handle and leading to the chamber, a spring closed 80 valve for controlling the vacuum connection mounted slidably in the handle provided with means for admitting air to the chamber when the connection is closed, a head disposed within the chamber and having a conical 85 socket in the under part thereof for receiving the cap, and means on the outside of the casing whereby the head may be manually operated to screw the cap on the neck of the container while the casing is under vacuum. 90

Signed at Evansville, Indiana, this 17th day of July, 1931.
